DESIGN FOR WALL-PAPER.

Design No. 13,147, dated August 8, 1882.

UNITED STATES PATENT OFFICE.

EDUARD LEISSNER, OF NEW YORK, N. Y.

DESIGN FOR WALL-PAPER.

SPECIFICATION forming part of Design No. 13,147, dated August 8, 1882.

Application filed June 30, 1882. Term of patent 3½ years.

To all whom it may concern:

Be it known that I, EDUARD LEISSNER, of New York, in the county and State of New York, have invented a new and Improved Design for Wall-Paper and Similar Fabrics, of which the following is a specification.

This invention relates to a new and original design for wall-paper and similar fabrics; and it consists in the novel grouping and configuration of parts hereinafter more fully described.

The accompanying photograph illustrates a face view of a wall-paper having my new design.

The figure L is a rosette-like figure, composed of alternate leaves and projecting balls set on stems. The figure H resembles a fanciful leaf in a circle, which is surrounded by dots in an octagon. The figure a is rectangular and made

up of smaller rectangles. The repetition of these figures—the figure a forming a lozenge-like center, and having a figure L set on each one of two of its opposite sides and a figure H set on each of the two remaining sides—forms the design.

I claim—

1. The design for wall-paper, consisting of the figure L, substantially as shown.
2. The design for wall-paper, consisting of the figure H, substantially as shown.
3. The design for wall-paper, consisting of the figures L, H, and a, substantially as shown.

EDUARD LEISSNER.

Witnesses:

RUDOLF KLEEMANN,
WILLY G. E. SCHULTZ.
